DESIGN FOR A VENDING MACHINE OR SIMILAR ARTICLE

William W. Evans, Elizabeth, N. J., assignor to Schnebbe Fire Protection Engineering Corporation, New York, N. Y., a corporation of New York

Application May 3, 1941, Serial No. 100,756

Term of patent 7 years

To all whom it may concern:

Be it known that I, William W. Evans, a citizen of the United States of America, residing in Elizabeth, Union County, New Jersey, have invented a new, original, and ornamental Design for Vending Machines or Similar Articles, of which the following is a specification, reference being had to the accompanying drawing, forming part thereof.

In the drawing:

Figure 1 is a front elevation of a vending machine or similar article showing my new design;

I claim:

The ornamental design for a vending machine or similar article, substantially as shown.

WILLIAM W. EVANS.
